UNITED STATES PATENT OFFICE.

HAROLD W. HODGETTS, OF SPRINGFIELD, MASSACHUSETTS, ASSIGNOR TO LEON J. HARLEY, JR., OF SPRINGFIELD, MASSACHUSETTS.

DESIGN FOR A CASKET-HANDLE.

56,558.

Specification for Design.

Patented Nov. 9, 1920.

Application filed February 26, 1920. Serial No. 361,563. Term of patent 14 years.

To all whom it may concern:

Be it known that I, HAROLD W. HODGETTS, a citizen of the United States of America, residing at Springfield, in the county of Hampden and Commonwealth of Massachusetts, have invented a certain new, original, and ornamental Design for a Casket-Handle, of which the following is a specification, reference being had to the accompanying drawing, forming a part thereof.

The figure is a plan view, partly in perspective, of the casket handle showing my new design.

I claim:

The ornamental design for a casket handle, as shown.

HAROLD W. HODGETTS.
